UNITED STATES PATENT OFFICE

170,292

TELEVISION CONSOLE CABINET

George Trautvetter, Jenkintown, Pa., assignor to
Heintz Manufacturing Company, Philadelphia,
Pa., a corporation of Pennsylvania

Application March 25, 1953, Serial No. 24,192

Term of patent 3½ years

(Cl. D56—4)

To all whom it may concern:

Be it known that I, George Trautvetter, a citizen of the United States of America and a resident of Jenkintown, Pennsylvania, have invented a new, original, and ornamental Design for Television Console Cabinet, of which the following is a specification, reference being had to the accompanying drawings, forming a part thereof.

Fig. 1 is a perspective view of a television console cabinet showing my new design;

Fig. 2 is a side elevational view thereof;

Fig. 3 is a top plan view thereof; and

Fig. 4 is an enlarged detail section taken on the line 4—4 of Fig. 1.

I claim:
The ornamental design for a television console cabinet, as shown.

GEORGE TRAUTVETTER.
